COMBINED MUSIC BOX AND CIGARETTE HOLDER

Olga Sanchez, 1940 W. Imperial Highway,
Los Angeles, Calif. 90047

Filed Aug. 5, 1966, Ser. No. 3,395

Term of patent 14 years

(Cl. D85—2)

FIG. 1 is a perspective view of a cigarette box, showing my design;

FIG. 2 is a side elevational view, the opposite side being a mirror image of the side shown;

FIG. 3 is a top view; and

FIG. 4 is a bottom view thereof.

The winding key shown in broken lines in FIGS. 1 and 2 for illustrative purposes is omitted from FIG. 4 to expose the hole through which it extends.

I claim:

The ornamental design for a combined music box and cigarette holder, substantially as shown and described.
